GUIDING DEVICE FOR PLOW-MOTORS.

1,175,574.

Specification of Letters Patent. Patented Mar. 14, 1916.

Application filed March 22, 1909. Serial No. 485,103.

To all whom it may concern:

Be it known that we, EDWIN M. WHEELOCK, residing at Minneapolis, in the county of Hennepin and State of Minnesota, 5 EMERY F. WHEELOCK, residing at Northfield, in the county of Rice, in said State, and DICKINSON O. WHEELOCK, residing at Minneapolis, in the county of Hennepin, in said State, all citizens of the United States, 10 have jointly invented certain new and useful Improvements in Guiding Devices for Plow-Motors, of which the following is a specification.

Our invention relates to traction engines 15 or motors used in plowing; and its object is to provide means for guiding the motor to cause it to travel at a proper distance from and along the side of a previously formed furrow. This object we accomplish 20 by means of an independent wheel or rotary disk supported a suitable distance in front of the motor and adapted to contact with the unplowed side of a furrow and thereby guide the motor.

Our improvement is illustrated in the 25 accompanying drawings, in which—

Figure 1 is a plan view and Fig. 2 a side elevation of an engine or motor embodying our improvement, showing the guide wheel 30 in operative position and locked against rotation on the vertical axis of its stock or support; Fig. 3 is a view similar to Fig. 2 but showing the guide wheel unlocked and free to rotate on such axis; Fig. 4 is an 35 enlarged front view of the guide wheel and its connections; Figs. 5 and 6 are details of the guide wheel carrier and its support; and Fig. 7 is a detail view of the devices 40 for turning the guide wheel on its vertical axis.

We have selected for the purpose of illustration, and have shown in the drawings in somewhat diagrammatic form, an explosive-engine motor, which is the type of motor 45 we prefer to use for plowing, but our improvements are adapted to be used in connection with motors of other types.

In the drawings 1 designates the main frame of the motor, 2 a housing for the 50 explosive-engine and driving-gear, 3 a seat thereon for the operator, 4 the rear wheels, 5 the front wheels, 6 the divided front axle, 7 the angular axle arms pivoted

to the axle 6, and 8 the equalizing bar for the pivoted arms 7. To these arms 55 are fastened the ends of a cable 9 which runs around a pulley 10 on the end of an operating rod 11 that is journaled in boxes 12 and 13 on the axle 6 and on a support 14 and is provided with a hand-wheel 60 15 in convenient position for an operator on the seat 3. A gang of plows (not shown) may be connected to the motor frame in the customary way by the chains 16, or rods, or other suitable means, to enable the motor 65 to draw the gang for plowing. All of these parts may be of any usual or suitable construction.

To relieve the operator of the strain and labor of giving constant attention to the 70 steering devices while plowing in order that the motor and plows may move in proper direction with relation to the previously plowed ground, we provide a guide wheel 17 arranged a short distance in front of the 75 machine. The inner side of this wheel is beveled, as shown at 18, adapting it to bear against the land-side 19 of a furrow 20 to prevent the motor from moving away from the furrow; and the operator can, by setting the steering-gear in position to give the 80 motor a slight tendency to move in that direction, obviate any tendency of the motor to move in the opposite direction, or toward the plowed ground. Such guide wheel 85 is not only an aid to the operator in steering the machine, but in effect is made to serve as a positive and practically automatic guide for the machine during the plowing along the side of a previously 90 formed furrow. The guide wheel shown has a very narrow tread and it may be a mere plate or disk with a beveled side, and may have a comparatively sharp edge 95 adapted to cut into the bottom of the furrow, or it may have a tread wide enough to adapt it to roll on the furrow bottom. And it may be arranged to be held in suspension with its edge or tread above the furrow bottom, or be free to cut into or 100 roll on the bottom of the furrow, without affecting the character of its operation as a guiding device for the motor.

In the construction illustrated the guide wheel 17 is mounted, somewhat in the manner of a caster-wheel, in a yoke 21 provided

on the lower end of an axis 22, so that it may not only rotate on its own axis but also turn on its vertical axis or pivot. The axis 22 has its bearing in a journal-box 23 on the forward end of a carrier-bar 24, pivoted preferably on an extension of the spindle 25 of one of the motor steering wheels, and braced by a stay-brace 26 that is connected to the axle arm 7 between the wheel and frame. The lower portion of the box 23 is provided with a notch or off-set 27 for engaging a corresponding notch or off-set 28 on the top of the stock 29 of the caster to constitute the two members of a clutch for locking the axis 22 against turning. A collar 30, held in place by a set-screw 31, limits the lengthwise movement of the axis in the box 23. Obviously, when the clutch members 27 and 28 are in engagement, the member 27 being fixed to the bar 24, the axis 22 cannot rotate, but that when the clutch members are disengaged (see Fig. 4) the axis 22 is free to rotate.

Ordinarily while plowing the clutches are engaged (see Fig. 2), but at times it is desirable that they be separated (as in Fig. 3) to enable the operator to turn the wheel as he may desire to regulate its course of travel, and so guide the motor. The devices provided to that end are the following: On the upper end of the axis 22 is a chain-wheel 32, the hub 33 of which is secured to the axis by a set-screw 34, and the wheel is engaged by a chain 35. To the ends of the chain are attached the ends of a cable 36 that runs on a sheave 37 carried by a spindle 38. The latter is supported by a step on a bracket 39 projecting outward from the under side of the frame 1 to a point vertically above the pivot of the axle arm 7, and it is also journaled in a box provided on a similar bracket 40 extended from the upper side of the frame. On the spindle is a bevel gear 41 and in mesh therewith is a bevel pinion 42 carried on the end of an operating rod 43 which is journaled in a box 44 attached to the frame 1 and in a box 45 on a support 46, and a hand-wheel 47 is provided on the rod in convenient position for the operator to turn it for controlling the course of the guide wheel when the clutch is disengaged.

For raising and lowering the carrier 24 to operate the clutch it is slidably supported on a curved support 48, which is connected to the axle 6 by a universal joint 49, and a cable 50 fastened to the support near the middle is extended rearward and upward over a pulley 51 on a standard 52 and thence downwardly to the end of an operating lever 53. The lever is fulcrumed to the frame near the seat 3 and arranged to be locked in positions of adjustment at the side of a quadrant 54 in the usual way. Instead of attaching the cable directly to the support

it is preferable to connect it by means of a coil spring 55.

To enable the carrier 24 to adjust itself along its support as required when the direction of travel of the steering wheels is changed, anti-friction rollers 56 and 57, one of which is supported from the carrier bar by a pair of brackets 58, and the other of which is journaled in the flange of the bar, engage the upper and rear surfaces of the support 48 and allow the carrier to move freely thereon in lateral direction.

In operation, while plowing at the side of a previously made furrow, the guide wheel runs on the bottom of the furrow with its beveled side adapted to properly contact with the land-side whenever the course of the motor is such as to cause such contact, and the operator is able, by lifting the carrier to disengage the clutch members and then by turning the rod 43, to adjust the inclination of the guide wheel relative to the direction of the motor movement as may be required. At the end of a furrow he may, as he wishes, either lift the guide wheel from the ground, or, when the conditions permit, allow it to remain on the ground and be free to adjust itself to the course of movement taken by the motor.

Having described our invention, what we claim and desire to secure by Letters Patent is—

1. The combination with a plow motor, of a guide wheel arranged to run in a furrow and bear against the land-side thereof in advance of the motor, a carrier for the guide wheel, a vertical axis providing the bearings for such wheel, means for turning the axis to vary the inclination of the guide wheel, a clutch, one member of which is carried by said axis and the other by said carrier, and means for raising and lowering the carrier to move the upper clutch member from and to engagement with the lower member.

2. The combination with a traction engine, of a guide wheel having its inner side adapted to bear against the land-side of a furrow, a carrier therefor, a steering axle, a locking device controlled by movement of said carrier for preventing such axle from being effectively turned, and means for raising and lowering said carrier to release or lock said locking device.

3. The combination with a plow motor, of a guide wheel adapted to run in a furrow and bear against its land-side, a vertical axis providing the bearings for such wheel, means for turning the axis to vary the inclination of the guide wheel, a carrier for such wheel arranged in front of the motor, a locking device, one member of which is carried by said axis and the other by said carrier for preventing the axis from turning, and means for raising and lower-

ing said carrier to release or lock the locking device.

4. The combination with a plow motor, of a guide wheel adapted to run in a furrow and bear against its landside, a vertical axis providing the bearings for such wheel, means for turning the axis to vary the inclination of the guide wheel, a carrier for such wheel arranged in front of the motor, a locking device, one member of which is carried by said axis and the other by said carrier for preventing the axis from turning, and means for raising and lowering said carrier to release or lock the locking device, and to raise and lower the guide wheel from and to the ground.

5. The combination with a plow motor, of a guide wheel adapted to run in a furrow and bear against its land-side, a vertical axis providing the bearings for such wheel, a sprocket-wheel thereon, an operating chain engaging therewith for turning said axis, a carrier for the guide wheel arranged in front of the motor, a locking connection, one member of which is carried by said axis and the other by said carrier for preventing the axis from turning, and means for raising and lowering said carrier to release or lock the locking connection.

30 6. The combination with a plow motor, of a guide wheel adapted to run in a furrow and bear against its land-side, a vertical axis providing the bearings for such wheel, means for turning the axis to vary the inclination of the guide wheel, a carrier for such wheel arranged in front of the motor, locking means for said guide wheel, the effect of which is dependent upon the position of said carrier, a pivoted support for the carrier, and operating connections with such support for raising and lowering the carrier and with it the guide wheel and its connections.

7. The combination with a plow motor, of a guide wheel carrier arranged at the front thereof, a vertical axis journaled thereon, a yoke extending downwardly from said axis, a vertically arranged guide wheel mounted in the yoke and adapted to bear against the land-side of a furrow, a locking connection controlled by said carrier for preventing such axis from turning, and

means for raising and lowering said carrier to release or lock said locking connection.

8. The combination with a plow motor, of a guide wheel carrier arranged at the front thereof, a vertical axis journaled thereon, a yoke extending downwardly from said axis, a guide wheel mounted in the yoke and adapted to bear against the land-side of a furrow, a clutch, one member of which is carried by said axis and the other by said carrier, and means for raising and lowering the carrier to move the upper clutch member from and to engagement with the lower member.

9. The combination with a plow motor including steering wheels, a divided axle and steering gear, a guide wheel adapted to run in a furrow and bear against its land-side, a carrier therefor pivoted to the axis of one of the steering wheels and extending in front of the motor, locking means for said guide wheel the effect of which is dependent upon the position of said carrier, a pivoted support on which the carrier is free to move laterally, and means for raising and lowering the guide wheel and its connections.

10. The combination with a traction engine having oscillatable steering wheels, hand operative means for oscillating said wheels, a carrier operatively connected to said wheels, a furrow pilot wheel mounted in said carrier, and a separable connection controlled by the rising and falling of said carrier controlling the guiding effect of said pilot wheel upon said oscillatable steering wheels.

11. The combination with a traction engine having oscillatable steering wheels, hand operative means for oscillating said wheels, and a furrow pilot wheel having connections, including a carrier and locking means, for oscillating said wheels, the locking means being rendered effective or ineffective according to the position of the carriers.
